STORAGE RACK FOR TOILET TISSUE OR THE LIKE

George Shaw, Fresh Meadows, N.Y., assignor to Wire World, Inc., Bronx, N.Y.

Filed Feb. 11, 1971, Ser. No. 114,745

Term of patent 3½ years

Int. Cl. D6—06

U.S. Cl. D6—97

FIG. 1 is a right side perspective view of a storage rack for toilet tissue or the like showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a rear elevational view thereof.

I claim:

The ornamental design for a storage rack for toilet tissue or the like, substantially as shown.
